SPEED-RESPONSIVE PRESSER DEVICE FOR
SEWING MACHINESBerthold P. Pinkvoss, Stratford, Conn., assignor
to The Singer Manufacturing Company, Elizabeth, N. J., a corporation of New Jersey

Application April 5, 1948, Serial No. 19,063

15 Claims. (Cl. 112—235)

1 This invention relates to sewing machines and more particularly to presser mechanisms therefor.

It is recognized, in the sewing machine art, that the speed of operation of a sewing machine is a factor as to the amount of pressure required to be placed upon the presser-foot of a sewing machine to cause it to hold the work in contact with the throat-plate and feed-dog, and to effect accurate feeding of the work. This is particularly true in sewing machines provided with the so-called alternating presser mechanisms which include two presser-feet so connected together that the pressure of the one on the work reacts to lift the other. In presser mechanisms of this nature, it is common practice to give to one presser-foot, frequently called the "walking" foot, work-engaging and work-releasing movements and feed-and-return movements in synchronism with the similar movements of a four-motioned feed-dog which engages the under side of the work, whereby the work is gripped between the two feeding elements and positively advanced. The non-feeding presser-foot is caused to bear upon the work, to hold the work stationary on the throat-plate while the feeding presser-foot is lifted, and to be raised above the work by the pressure of the feeding foot on the work. Thus the two presser-feet alternately engage and release the work. One or more springs are commonly employed to press the presser-feet upon the work to cause the feeding foot to assist the feed-dog in feeding the work and to cause the non-feeding presser-foot to clamp the work on the throat-plate during the time the needle is in the work, i. e., between feed strokes of the feeding elements.

It has been found, that when using normal spring pressure on alternating presser mechanisms, that because of the inertia of the parts, friction, and the inability of the presser spring to react sufficiently quickly when operating at high speeds, the presser-foot would not bear upon the work but would gradually be raised higher and higher until the feeding foot would, in effect, "paw the air" above the work with the result that the work was not properly clamped and fed thereby. This difficulty was overcome, to a large extent, by greatly increasing the spring pressure on the presser-feet which, however, had the undesirable effect of overloading the machine and of requiring excessive work by the operator to lift the presser-feet for insertion and removal of the work. It also produced the undesirable effect of causing the work to be scored by the

feeding-foot when the machine was operating at relatively slow speeds.

This invention has as a primary object to overcome the defects and undesirable features of prior constructions of this nature.

Another object of the invention is to provide an alternating presser mechanism which will securely hold the work on the throat-plate between successive feeding strokes of the feeding device; which will effect positive and accurate feeding of the work under all speeds of operation; and which will prevent overloading of the machine and scoring of the work under slow speed operation.

15 These objects have been attained by providing a presser mechanism which exerts a relatively light pressure on the presser-foot when the machine is operated at relatively slow speeds and which automatically increases the pressure in proportion to increases in speed.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

30 In the drawings,

Fig. 1 is a side elevation, partly broken away and partly in section, of a sewing machine embodying the present invention; the machine being illustrated as at rest.

35 Fig. 2 is a left end elevation, partly broken away, of the machine illustrated in Fig. 1.

Fig. 3 is an enlarged sectional view of the mid-portion of Fig. 1 with certain of the parts in the positions they assume under high speed operation.

40 Fig. 4 is an enlarged transverse sectional view taken substantially on the line 4—4 of Fig. 1.

Fig. 5 is an enlarged transverse sectional view taken substantially on the line 5—5 of Fig. 1.

45 Fig. 6 is a detail sectional view, taken on the line 6—6 of Fig. 2, showing the means for connecting the presser spring with the alternating presser mechanism.

Fig. 7 is a detail sectional view taken substantially on the line 7—7 of Fig. 2 showing the means for connecting the alternating presser-bar lifting lever to the supporting bar of the non-feeding presser-foot.

Referring more specifically to the drawings, 55 the invention is disclosed as embodied in a sew-

ing machine comprising a frame including a work-supporting plate 1, a standard 2 secured to and rising from the plate 1. Formed integrally with the standard is an overhanging bracket-arm 3 which terminates, at its free end, in a bracket-arm head 4, journaled lengthwise within the bracket-arm is a main or needle-bar driving shaft 5 which carries, at its rear end, a combined belt and hand wheel 6 having a belt groove 7 adapted to receive a driving belt (not shown), by means of which the shaft may be driven from any suitable source of power. Reciprocably mounted in bearings 8 and 9 in the bracket-arm head 4 is a needle-bar 10 carrying, at its lower end, a thread-carrying eye-pointed needle 11 adapted to cooperate with a suitable loop-taker (not shown) in the formation of stitches. The needle-bar is reciprocated from a crank-disk 12, secured on the shaft 5, by conventional means designated generally as α .

The machine is also provided with an alternating presser mechanism including a presser-bar 13, mounted for vertical reciprocation in the bracket-arm head 4, and carrying at its lower end a non-feeding presser-foot 14 adapted to hold the work on the usual throat-plate 15 carried by the work-supporting plate 1. Cooperating with the presser-foot 14 is a combined presser- and work-feeding-foot 16 which cooperates with the feed-dog f of a conventional four-motioned work-feeding mechanism. The foot 16 is secured upon the lower end of a feed-bar 17 the upper end of which is fulcrumed, at 18, to one arm 19^a of a three-armed lever 19. The feed-bar 17 and the feeding presser-foot carried thereby are given rising-and-falling and feed-and-return movements from eccentrics 20 and 21, respectively, secured upon the main shaft 5. The eccentric 20 is surrounded by the strap end 22^a of a downwardly and rearwardly inclined pitman 22 the other end of which is pivotally connected to the upper free end of a feed-lift rock arm 23 clamped upon a sleeve 24 journaled at one end in the bracket-arm head 4 and at its other end in a bracket 25 secured to and depending from the under side of the bracket-arm 3. The outer end of the sleeve 24 carries an upright arm 26 which is connected, by a link 27, to the upstanding arm 19^b of the three-armed lever 19. The third arm 19^c of the lever 19, is connected by an anchor link 27^a to a pin 28 secured in the bracket-arm head 4. A vertically disposed link 29 is pivotally connected, by the stud 30 with the third arm 19^c of the lever 19, with a collar 31 secured by pinch joint 32 on the upper end of the presser-bar 13. From the foregoing it will be understood that rotation of the shaft 5 and the eccentric 20 thereon will cause the link 19 to be oscillated back and forth about the pivot screw 18 and stud 30 thereby alternately raising and lowering the presser-bar 13 and feed-bar 17.

Back and forth feed-and-return movements are given to feed-bar 17 from the eccentric 21 on the shaft 5 by means now to be described. A downwardly and rearwardly inclined pitman 33 has its upper strap end surrounding the eccentric 21 and its lower end pivotally connected with the upper free end of a rock-arm 34 secured upon the rear end of a feed-drive rock shaft 35 journaled within the sleeve 24.

At its forward end the feed-drive rock-shaft 35 has secured to it the hub end of a depending feed-drive rock-arm 36, the lower end of which is pivotally connected, at 37, to one end of a link 38 the other end of which is pivotally con-

nected, at 39, with the feed-bar 17. Thus rotation of the shaft 5 effects, through the mechanism above described, feed and return movements of the feed-bar and the feeding presser-foot carried thereby, in timed relation with the rising and falling movements thereof. These movements cause the foot 16 to be moved into contact with the work to be fed rearwardly, elevated and returned to its forward position in synchronism with the corresponding movements of the feed-dog f .

As in other alternating presser mechanisms of this nature, rocking of the three-armed lever 19 clockwise as seen in Fig. 2, depresses the foot 16 into contact with the work. When further downward movement of the foot is prevented further movement of the lever in the same direction causes the lever to turn about the fulcrum and thereby lift the presser-foot 14 clear of the work. In this position of the parts the feeding-foot 16 is given its rearward feeding stroke in synchronism with the feeding stroke of the feed-dog f . After the feeding stroke is completed the lever 19 is oscillated in the opposite direction thereby depressing the foot 14 upon the work and lifting the feeding foot 16 to permit it to be returned to its forward position.

The presser-feet 14 and 16 are normally depressed upon the work by a leaf spring 40, supported at its rear end on a bracket 41 secured to the under side of the bracket-arm 3, as shown most clearly in Fig. 5. The forward end of the spring 40 extends into the bracket-arm head 4 and is connected, by a bolt 42, (see Fig. 6) with a stud 43 carried by the three-armed lever 19, which, as hereinbefore explained is connected with both the presser-bar 13 and the feed-bar 17. Intermediate its ends, the spring 40 is engaged by a shoe 44 which is pressed downwardly, to tension the spring 40, by its engagement with the lower unthreaded end 45^a of a screw stud 45. This stud is threaded into a bushing 46, which, in turn, is threaded into the lower wall of the bracket-arm 3. The upper end of the stud is provided with a screw driver slot whereby the stud may be rotated to adjust it axially, thereby to shift the shoe 44 vertically to vary the downward pressure exerted by the spring 40 on the presser-bars. This pressure will remain constant for any given adjustment of the stud 45. Preferably the stud 45 will be adjusted to produce a downward pressure on the presser-feet which is most suitable for relatively slow speed operation of the sewing machine.

This invention has provided automatic means for varying the total downward pressure transmitted to the presser-feet 14 and 16 in proportion to the speed of operation of the machine. This means comprises an auxiliary spring device which acts in conjunction with the main spring device 40 to increase the spring pressure as the speed of the machine is increased. The auxiliary spring device includes a lever 47 preferably, but not necessarily, in the form of a second leaf spring located between the spring 40 and the bracket-arm 3. The forward end portion of the spring extends into the bracket-arm head 4 and bears upon the spring 40, as shown most clearly in Fig. 1. The rear end of the lever 47 is bifurcated, and straddles the inverted T-shaped lower end 48^a of a twisted link 48, the upper end of which is pivotally connected at 49 to one arm 50^a of a bell-crank lever 50, journaled on a stud 51 supported by the bracket-arm. Intermediate its ends 70 the spring lever 47 is in contact with the lower

end of the bushing 46, hereinbefore mentioned which under certain conditions, serves as a fulcrum for the spring 47. This bushing is so located and arranged that in the lowermost position of the link 48, as shown in Fig. 1, the spring 47 is substantially tension-free and therefore transmits little, if any, pressure to the spring 40.

An upper arm 50^b of the bell-crank lever 50 has a head portion 50^c located between and engaging an annular flange 52^a, forming a part of a sleeve 52 slidingly mounted on the shaft 5, and a thrust bearing 53 mounted on the sleeve 52. Secured upon the shaft 5, as by set screws 54, is a collar 55 having pairs of spaced and oppositely extending ears 56, 57 between which are mounted, on pivot pins 58, 59, angle levers 60, 61. Inwardly extending arms 60^a and 61^a of the levers 60 and 61, respectively, engage a thrust ring 62 surrounding the shaft 5. The other arms of the levers 60, 61 carry weights 63 and 64, respectively. Slidingly mounted in the collar 55 are four thrust pins 65 which are engaged, at one end, by the thrust ring 62. The opposite ends of the pins 65 bear upon one end of the sliding sleeve 52. A coil spring 66, surrounding the shaft 5 and interposed between the flange 52^a at the rear end of the sleeve 52 and a driving pulley 67 secured to the shaft 5, offers a certain amount of resistance to movement of the sleeve 52 for a purpose hereinafter to be described.

Operation

Assuming that the screw stud 45 has been adjusted to give to the main leaf spring 40 sufficient tension to cause the alternating presser mechanism to function properly at a limited range of relatively slow speeds, the bushing 46 is adjusted to a position in which it bears lightly upon the spring 47. Then, when the machine is put into operation the presser-feet will be depressed mainly by the spring 40. Rotation of the main shaft 5 and the collar 55 thereon will tend to cause the weighted ends of the levers 60 and 61 to move outwardly under centrifugal force from the position illustrated in Fig. 5. The pressure of the spring 66 on the sliding sleeve 52 temporarily holds the sleeve 52, pins 65 and thrust ring 62 from moving to the right, as seen in Fig. 1. Thus the levers 60 and 61 are prevented from swinging outwardly until a predetermined accelerated speed of rotation has been attained and the centrifugal force exerted on the levers is sufficient to overcome the pressure of the spring 66. The range of speeds from zero up to the speed at which the centrifugal force on the levers 60 and 61 begins to overcome the pressure of the spring 66 corresponds to the range of speeds under which the main spring 40 will exert a sufficient pressure on the presser-feet 14 and 16 to cause them to function properly. After the predetermined accelerated speed has been attained, a further increase in speed will cause the weighted levers 60, 61 to swing outwardly whereupon the ends 60^a and 61^a of those levers will shift the thrust ring 62, pins 65, and sleeve 52 to the right, as seen in Fig. 3. This causes clockwise turning of the bell-crank lever 50, whereupon the link 48 and the rear end of the spring lever 47 are lifted. The lever 47 fulcrums about the under side of the head 46^a of the bushing 46 thereby depressing the forward end of the lever and adding to the downward pressure exerted on the presser-feet by the leaf spring 40. Inasmuch as the lever 47 is made of spring metal there will be

a certain amount of resiliency therein which will prevent abrupt changes in pressure transmitted to the presser-feet. The extent to which the weights 63 will be swung outwardly and therefore the amount of pressure which the spring lever 47 will transmit to the leaf spring 40 will be proportional to the speed of rotation of the main shaft 5. Under maximum speed of rotation of the main shaft the weights 63, 64 and levers 60, 61 will assume the positions shown in Fig. 3, and the full pressure of both the leaf spring 40 and the spring lever 47 will be transmitted to the presser-feet 14 and 16.

From the foregoing it will be perceived that this invention has provided simple means for automatically transmitting to the alternating presser-feet downward pressure in amount required to effect the most efficient operation thereof under all speeds of operation of the sewing machine, from slow speed to maximum speed.

Having thus set forth the nature of the invention, what I claim herein is:

1. In a sewing machine, in combination, a work-support; a variable speed rotary shaft; a presser mechanism yieldingly biased downwardly toward said work-support; and mechanism actuated by said shaft and rendered effective at increasing speeds of rotation thereof for amplifying the downward pressure exerted by said presser mechanism.
2. In a sewing machine, in combination, a frame; a variable speed rotary shaft journaled in said frame; a presser mechanism supported by the frame; a member pivotally supported by said frame and connected with said presser mechanism; and means actuated by said shaft and responsive to the variations in speed thereof for turning said member about its pivot to cause it to transmit varying downward pressures to said presser mechanism.
3. In a sewing machine, in combination, a frame; a variable speed rotary shaft journaled in said frame; a presser mechanism supported by the frame; a lever fulcrumed intermediate its ends on said frame, one end of said lever being connected with said presser mechanism; and speed responsive means connected to the other end of said lever and actuated by said shaft for turning said lever about its fulcrum to cause it to transmit downward pressure on said presser mechanism in proportion to the speed of rotation of said shaft.
4. In a sewing machine, in combination, a variable speed rotary shaft; a presser-foot; spring means exerting a downward pressure on said presser-foot; and auxiliary means actuated by said shaft and responsive to variations in the speed thereof for amplifying the pressure exerted by said spring means in direct proportion to the variations in the speed of said shaft.
5. In a sewing machine, in combination, a variable speed rotary shaft; a presser-foot; spring means exerting a predetermined downward pressure on said presser-foot; and auxiliary means actuated by said shaft and rendered effective by an increase in the speed of rotation thereof for amplifying the pressure exerted by said spring means.
6. In a sewing machine, in combination, a variable speed rotary shaft; a presser-foot; a first spring means exerting a predetermined downward pressure on said presser-foot; and auxiliary means rendered effective by an increase in the speed of rotation of said shaft for amplifying the pressure exerted by said first spring means in

proportion to the increase in speed of said rotary shaft.

7. In a sewing machine, in combination, a rotary shaft; an alternating presser mechanism including a first presser-foot having vertical movements only and a second presser-foot having vertical movements and horizontal feed and return movements; spring means normally transmitting to said presser mechanism a predetermined downward pressure; and auxiliary means actuated by said shaft and rendered effective when the speed of rotation of said shaft reaches a predetermined rate for amplifying the pressure transmitted to said presser mechanism by said spring means.

8. In a sewing machine, in combination, a variable speed rotary shaft; an alternating presser mechanism including a first presser-foot having vertical movements only and a second presser-foot having vertical movements and horizontal feed and return movements; spring means normally transmitting to said presser mechanism a predetermined downward pressure; and auxiliary means actuated by said shaft and rendered effective when the speed of rotation of said shaft reaches a predetermined rate for variably amplifying the pressure transmitted to said presser mechanism by said spring means in proportion to increases in the speed of rotation of said shaft.

9. In a sewing machine, in combination, a variable speed rotary shaft; an alternating presser mechanism including a first presser-foot having vertical movements only and a second presser-foot having vertical movements and horizontal feed and return movements; spring means normally transmitting to said presser mechanism a predetermined downward pressure; and auxiliary means actuated by said shaft when the shaft has attained a predetermined speed of rotation for amplifying the pressure transmitted to said presser mechanism by said spring means.

10. In a sewing machine, in a combination, a variable speed rotary shaft; a presser mechanism; means exerting a substantially constant downward pressure on said presser mechanism; a pair of speed-responsive elements carried by said shaft; and means actuated by said speed-responsive elements for transmitting to said presser mechanism additional downward pressure in amounts proportional to the speed of rotation of said shaft.

11. In a sewing machine, in combination, a variable speed rotary shaft; a presser mechanism; spring means exerting a substantially constant downward pressure on said presser mechanism; a pair of bell-crank levers carried by and rotatable with said shaft; a weight carried by one arm of each of said levers, said levers being arranged to be swung about their fulcrums by the centrifugal force exerted by said weights; and means actuated by the other arms of said levers for transmitting to said presser mechanism additional downward pressure in amounts proportional to the speed of rotation of said shaft.

12. In a sewing machine, in combination; a variable speed rotary shaft; a presser mechanism; spring means exerting a substantially constant downward pressure on said presser mechanism; a pair of speed-responsive elements carried by said shaft; a sleeve slidably mounted on said shaft; means actuated by said speed-responsive

elements for shifting said sleeve axially of said shaft; and means actuated by the sliding movement of said sleeve for transmitting to said presser mechanism additional downward pressure in amounts proportional to the speed of rotation of said shaft.

13. In a sewing machine, in combination, a frame; a variable speed rotary shaft; a presser mechanism; means exerting a substantially constant downward pressure on said presser mechanism; a collar fixed to said shaft; a pair of speed-responsive elements carried by said collar; a lever fulcrumed on said frame; a member slidably mounted on said shaft and engaging said lever; means actuated by said speed-responsive elements for shifting said member lengthwise of said shaft to turn said lever about its fulcrum; and means actuated by the turning movement of said lever for exerting additional downward pressure on said presser mechanism in amounts proportional to the speed of rotation of said shaft.

14. In a sewing machine, in combination, a frame; a variable speed rotary shaft; a presser mechanism; means exerting a substantially constant downward pressure on said presser mechanism; a collar fixed to said shaft; a pair of speed-responsive elements carried by said collar; a lever fulcrumed on said frame; a member slidably mounted on said shaft and engaging said lever; means actuated by said speed-responsive elements for shifting said member lengthwise of said shaft to turn said lever about its fulcrum; a spring acting on said member to prevent its being shifted by said speed responsive elements until a predetermined speed of rotation of said shaft has been attained; and means actuated by the turning movement of said lever for exerting additional downward pressure on said presser mechanism in amounts proportional to the speed of rotation of said shaft.

15. In a sewing machine, in combination, a frame including a bracket-arm; an abutment supported by said bracket-arm; a variable speed rotary shaft journaled in said frame; a presser mechanism mounted for vertical movement relative to said frame; means exerting a substantially constant downward pressure on said presser mechanism; a spring arm extending lengthwise of said bracket-arm and bearing intermediate its ends on said abutment, said spring-arm having one end thereof connected with said presser mechanism; a speed-responsive device carried by said shaft; and means actuated by said speed-responsive device and connected with the other end of said spring arm to cause the forward end of said arm to be put under compression thereby to transmit to said presser mechanism additional downward pressure in amounts proportional to the speed of rotation of said shaft.
